UNITED STATES PATENT OFFICE.

ORLYSTIS M. POTTER, OF LARNED, KANSAS.

COMBINATION-GARMENT.

973,299.

Specification of Letters Patent. Patented Oct. 18, 1910.

Application filed October 19, 1909. Serial No. 523,436.

To all who, it may concern:

Be it known that I, ORLYSTIS M. POTTER, a citizen of the United States, residing at Larned, in the county of Pawnee and State 5 of Kansas, have invented certain new and useful Improvements in Combination-Garments, of which the following is a specification.

My invention relates to improvements in 10 wearing apparel and more particularly to a combination suit comprising an outside or dress shirt and drawers.

The purpose of my invention is to combine in one suit a nether garment and a dress 15 shirt, so that the difficulties heretofore encountered when dispensing with suspenders and supporting the trousers by means of a belt, will be entirely overcome and the shirt will at all times remain in proper position 20 and without any tendency to rise out of the trousers or bulge at the waist line. One of the greatest objections to the substitution of a belt for suspenders has been this difficulty of controlling the movement of the outer 25 shirt at the waist line, which not only causes discomfort to the wearer but presents a very untidy appearance. Prior to my invention, there has been no practical solution of this 30 problem because the lower part of the shirt simply hung free below the waist line and was merely constrained by the constrictions 35 of the waist-bands of the trousers and drawers. The various movements of the body, however, and especially when bending over 40 or into a stooping posture, immediately drew the skirts of the shirt upwardly and upon resuming an erect position a considerable portion of the shirt which should be below 45 the waist was left in folds above the top of the trousers. This is entirely obviated by my present invention, and I believe myself to be the first to devise a suit which combines a dress shirt with the drawers. The construction by which I am enabled to carry 50 out this purpose will be more clearly understood by reference to the accompanying drawings, in which—

Figure 1 is a front elevation of one form 55 of my combination garment; Fig. 2 is a rear elevation of the same; Fig. 3 is a rear elevation of a modification of my invention; Fig. 4 is a pattern of the right-hand side of the garment shown in Fig. 3; and Fig. 5 is a front perspective view of my combined garment as it appears upon a person.

The garment is preferably made of such

ready-woven cloth or fabric and of a material suitable for the outside or dress shirt. The front portions 1, 1, are each made of integral pieces to form the upper outer shirt 60 portion and the lower nether drawer portion. In the form shown in Fig. 2, the back of the garment is formed of an upper outer shirt portion 2, united at the seam 3, with the two leg portions 4, 4. By referring to Fig. 2, 65 it will be observed that the top of each leg portion 4 is cut upon a curve and is higher at the center. The lower part of the shirt portion 2, however, is cut upon a straight line, and extends below the curved line 3 before 70 the shirt and drawers are sewed along the seam 3. It will be apparent that when the curved top of the leg portion is brought down and sewed to the straight bottom of the shirt portion, a fullness will be produced 75 over the seat. That is, the seat portion of each leg 4, has a greater amount of cloth than it would have if there were merely enough material to extend from the waist line to the bottom of the drawers. This fullness appears as a curved line when laid out 80 flat, the fullness increasing toward the center, but when the garment is on the person the fullness is taken up over the hips and the line 3, 3, becomes nearly straight around the 85 body. The portions 4 overlap only a short distance between the points 3^a and 3^b, forming flaps. By allowing a greater length along the inner side of each flap than the corresponding outer edge of the leg portion, I 90 am enabled to provide a sufficient fullness along the crotch flaps which overlap each other as shown. The edge of the flap on the left side of the back is shown in full lines and extends from the point 3^b, crossing the 95 center at 5, and at 6 passing forwardly between the legs, appearing at point 6, in the front view shown in Fig. 1. It will be evident from this construction that I have provided a maximum fullness and freedom 100 across the hips and through the crotch with a minimum of cloth, and that the construction indicated along the line of the seam 3, prevents any undue strains.

The front of the garment may be closed 105 from the neck opening to the crotch by means of buttons and eyelets 7, and the shirt portion may be provided with a plaited bosom or left plain as in the usual outing or negligée shirt.

My combination garment is more especially adapted for summer wear, and I have

therefore shown the drawers knee-length, although it is evident that the full-length drawers may be employed. For the purpose of supporting the hose, I provide straps 9 upon either side of the leg portion, to which may be buckled elastic supporters 10, as shown in Fig. 5. It will be observed that the downward pull of the garter upon the straps 9, is transmitted through the length of the 10 garment and assists in keeping it in proper position, free from any bunching about the waist line. This is an important feature, especially in a summer garment, providing an efficient support for the hose and avoiding 15 the use of encircling bands that tend to prevent the circulation of the blood. Furthermore, in warm weather the leg is usually bare, and it is unpleasant and unsanitary to use the leg-bands.

20 In Fig. 3, I have shown a modification of my invention in which the rear portion is formed of two integral parts 11, including both the shirt and drawers. In order to provide the requisite fullness across the hips and 25 in the crotch flaps, I provide a fold or plait 12, which is sewed into the side seams at 13 but is free to unfold through the seat portion and along the free inner edge of the flaps as illustrated at 14. With this construction there is no seam extending across 30 the back as in Fig. 2, the overlap for the crotch flaps being secured by passing the offset 16, extending from the side portion 11^a under the other portion and securing it at 18.

35 From the foregoing description it will be evident that I have provided a construction by which an outside or dress-shirt can be united with a pair of drawers, and the two

elements coöperate to form a perfect fitting garment for the body in any position which 40 the wearer may assume. As illustrated in Fig. 5, the trousers, shown in dotted lines, extend above the drawers portion so that no seam or fullness appears at the waist line. Moreover, the outer and inner portions of 45 the garment perform their usual functions, while each assists the other in maintaining a proper position upon the body without auxiliary supporting or adjusting devices.

I claim as my invention and desire to se- 50 cure by Letters Patent:—

As a new article of manufacture, a combination garment comprising an outside or dress shirt and a bifurcated nether garment, the front portion being integral throughout 55 the entire length and being united to the rear portion at the crotch by means of interlapping flaps integral with the rear portion, the rear pieces of said bifurcated nether garment having substantially the same amount of 60 cloth as the corresponding front portions above the waist line, but greater amount of cloth below the waist line by being made longer than the corresponding front portions but made to correspond in length with said 65 front portions where they are united thereto at the side seams, thus leaving said greater amount of cloth as a fullness through the seat portion.

In testimony whereof I affix my signature, 70 in presence of two witnesses.

ORLYSTIS M. POTTERF.
